UNITED STATES PATENT OFFICE.

MORRIS SHALANSKY, OF INDIANAPOLIS, INDIANA.

REGISTER FILTER.

Application filed December 10, 1926. Serial No. 153,994.

This invention relates to a register guard.

The chief object of this invention is to provide means for filtering the air discharged from a hot air register and for tempering the same.

The chief feature of the device consists in a rectangular framework for a rectangular register and positioning over the same for forming a continuing channel therefrom.

10 Said open framework supports in spaced relation to the register a filtering screen, the framework including in its lateral portion a suitable aperture for permitting lateral discharge of reflected and deflected air.

15 The full nature of the invention will be understood from the accompanying drawings and the following description and claim:

20 In the drawings Fig. 1 is a perspective view of the register guard. Fig. 2 is a transverse sectional view of the same mounted in position adjacent a register. Fig. 3 is a perspective view of a modified form of the invention. Fig. 4 is a vertical sectional view 25 through the same in position adjacent a register.

In Figs. 1 and 2 of the drawings 10 indicates a floor having an opening 11 receiving a register 12 with a perforated plate 13 30 through which the air discharges. The guard consists of a rectangular framework 14 having the side walls 15 whereby the framework 14 is positioned in spaced relation to the register plate 13 and said framework

35 14 peripherally supports a fine mesh screen 16. The spacing portion 15 is suitably apertured as at 17 and the same may be fully cut out or may be formed with deflecting portions 9 in the form of louvers. Extending 40 inwardly from the sides 15 and towards the open framework 14 is a deflector 18 which forms a trough 19 adapted to receive water.

With the resultant construction positioned over a register the air discharged there-through and therefrom impinges on screen 16 and the dirt and other particles and preventing their passing into the room and dis-coloring the walls and the like. The deflector 18 insures that the air which passes 50 adjacent the edges of the register is deflect-ed inwardly through the screen for screen-ing action. Such of the air as does not pass through the screen but is reflected or deflected in the attempt to escape, passes lat-

erally through the openings 17 and over the 55 trough 19 and takes up some of the water and thus humidifies or tempers the air in the entire room. The louvers 9 may be positioned as desired, and herein are shown op-positely directed from median planes so as 60 to secure better distribution of the air.

In Figs. 3 and 4 a modified form of the invention is illustrated, wherein the side 115 supports the open rectangular framework 114 and the screen 116. Said sides are pro-vided with the openings 117 having the louvers 109. Herein a deflector 118 is pro-vided adjacent the register plate 13 but is not coextensive with the rear edge of the framework 115, but is in spaced relation 65 thereto, whereby the lower portion of the guard may be cut out as at 121 to conform to the base board and quarter round. In this form of the invention the deflector 118 does not form a trough for containing water but 70 an additional trough 119 is provided in the upper portion and access thereto may be had through the opening 120.

The operation of the device is substantial-ly similar to that previously described with 80 reference to Fig. 1. That is, the direct pas-sage of air through the screen filters the same and the deflector 118 insures such passage. Such of the air which does not pass through the screen is deflected and passes laterally 85 from the guard through the openings.

The invention claimed is:

In combination with a register controlled channel and a supporting surface, of a regis-ter filter supported by said surface including 90 a wall peripherally enclosing the register and substantially inclosing the supporting sur-face and forming a continuation of the regis-ter controlled channel, said wall having a pluri-ality of openings near the top to dis-charge laterally of the channel, a filtering screen supported by said wall and substan-tially transverse to said channel and at the 95 top of said wall and an inwardly directed deflecting wall peripherally associated with the bottom of said wall and substantially co-extensive therewith for directing heated air from the register controlled channel inward-ly to the central portion of said filtering screen.

In witness whereof, I have hereunto af-fixed my signature.

MORRIS SHALANSKY.
